US00D920534S

(12) **United States Design Patent** (10) **Patent No.:** **US D920,534 S**
(45) **Date of Patent:** **** May 25, 2021**

(54) **BLOOD SAMPLE FILTRATION DEVICE**

(71) Applicant: **CanaryQ, Inc.**, Mountain View, CA (US)

(72) Inventor: **Estevan Mendoza**, Mountain View, CA (US)

(73) Assignee: **CanaryQ, Inc.**, Mountain View, CA (US)

(**) Term: **15 Years**

(21) Appl. No.: **29/674,574**

(22) Filed: **Dec. 21, 2018**

(51) LOC (13) Cl. **24-02**

(52) U.S. Cl.

USPC **D24/224**

(57) **CLAIM**

The ornamental design for a blood sample filtration device, as shown and described.

DESCRIPTION

FIG. 1 is a front perspective view of a blood sample filtration device.

FIG. 2 is a bottom perspective view of the device illustrated in FIG. 1.

FIG. 3 is a front view of the device of FIG. 1.

FIG. 4 is a back view of the device of FIG. 1.

FIG. 5 is a first side view of the device of FIG. 1.

FIG. 6 is a second side view of the device of FIG. 1.

FIG. 7 is a top view of the device of FIG. 1; and,

FIG. 8 is a bottom view of the device of FIG. 1.

1 Claim, 8 Drawing Sheets
